WORKMAN'S SAFETY APRON

Clarence W. Robertson, 1553 Harrison, Memphis, Tenn.
Filed Apr. 27, 1962, Ser. No. 190,570
3 Claims. (Cl. 2—51)

This invention relates to workmen's aprons and particularly relates to a yieldably fastened apron.

Each year thousands of productive man-hours are lost and many workmen are disabled or fatally injured because of industrial accidents. A relatively large number of industrial accidents are incurred as workmen's apparel becomes entangled in machines and the workmen pulled into the machines and injured. In the majority of these accidents, the company is financially responsible for accident losses, and the company suffers because of the lost time of the workmen. Subsequently, in their efforts to promote safety and to prevent such accidents as are brought about by loose apparel being caught in machinery, many companies have forbidden employees to wear aprons.

As a consequence of restricting use of aprons, workmen's clothes become prematurely soiled, thereby requiring more care in order to keep them neat and clean. The "no apron" regulation also indirectly causes more wear to the clothes of the workman, shortens their usefulness, and results in more frequent purchases of work clothes than is otherwise necessary when an apron is used to protect the clothes.

In order to overcome the above mentioned inconveniences as are caused by working without an apron, the principal object of this invention is, therefore, to provide a yieldably fastened apron that may be safely worn to protect the clothes of the workman.

A further object of the present invention is to provide an apron that has no strings to catch in moving machinery.

A further object is to provide an apron that is quickly freed from the workman in the event the apron becomes entangled in the machinery, thus reducing the likelihood of injury to the workman.

A further object is to provide an apron that is cooler and less hampering to the workman.

A further object is to provide an apron that is adapted to be easily and compactly folded for shipment or storage, or when not in use.

A further object is to provide an apron that is simply made and when constructed of inexpensive material may be disposed of after use.

The means by which the foregoing and other objects of the present invention are accomplished and the manner of their accomplishment will be readily understood from the following specification upon reference to the accompanying drawings, in which:

FIG. 1 is an illustration of the apron as worn by the workman.

FIG. 2 is an inward or backside view of the apron having a pair of yieldable tab fasteners with the left tab upward to illustrate the affixing seam, and with the right tab folded over and in a position as when in use.

FIG. 3 is a fragmentary enlarged sectional view of the tab portion of the apron taken as on the line III—III of FIG. 2; and, in addition, is shown a fragmentary sectional portion of the pants and shirt of the workman to illustrate the relationship of the tab portion therewith.

FIG. 4 is an inward or backside view of the apron having yieldable clip fasteners.

FIG. 5 is an enlarged fragmentary view of the clip fastener as viewed from the inward or backside of the apron and also showing a fragment of the apron body.

FIG. 6 is an enlarged sectional view taken as on the line VI—VI of FIG. 5 and shown attached to a belt.

2

Referring now to the drawings in which the various parts are indicated by numerals, the apron 11 of the present invention includes a body portion or body 13 which is preferably, though not necessarily, formed of a single elongated piece of flexible material. Apron 11 is constructed of fabric, synthetic plastic sheet, paper, or any like material having the necessary characteristics suitable to the particular environment of the work being done or to the needs of the workman.

10 Apron body 13 includes an upper portion 15, a lower portion 17, and an apron waist 19 intermediate the upper and lower portions. The edge of upper portion 15, as viewed in FIGS. 2 and 4, defines substantially a parabolic arc, with the symmetrical side edges beginning at 15 the top and extending downward and outward to join the rectangular lower portion 17 at waist 19. As mentioned previously, the body 13 of the apron may be formed of a single piece of material, though a closer fitting apron results when the upper portion 15 and the lower portion 17 are of separately formed pieces sewn together at waist 19. As is apparent, the upper portion 15 partially covers and protects shirt 21 of the workman, and the lower portion 17 partially covers and protects pants 23 with the lower portion transversely extending from one side of the workman's body to the other. The perimetric edge of body 13 is preferably folded inwardly and sewn to form a continuous hem 25. Hemming of the edge of body 13 is particularly desirable if the apron is constructed of thin fabric or plastic sheet material.

30 A button hole 27 is provided in upper portion 15 to engage a button 29 of shirt 21. Button hole 27 should be as close to the top edge of the apron as is practicable, thereby to provide a close-fitting upper portion 15. A

35 pair of laterally spaced fastening tabs 31, 33 are transversely attached adjacent the upper edges thereof on the inward side of body 13 at waist 19. Tabs 31, 33 are preferably substantially rectangular in shape and are preferably of the same material as apron body 13. In attaching tabs 31, 33 they are preferably positioned in the manner shown by the tab 31 in FIG. 2, and the tab is attached by sewing along the seam 35. From this sewing position above mentioned in which the main body of tab 31 is 40 extended upwardly or above seam 35 with the free edge 45 36 being upwardly, the tab is folded downward into its normal downward position, as shown by the tab 33 in FIG. 2. Tab 33 is preferably attached in a similar manner as above described for tab 31. For purposes of clarity, the flap portions of fastening tabs 31, 33, that is, 50 the portions which are not directly attached to body portion 13, are respectively designated as flap portions 37, 39.

55 Referring now to FIGS. 1, 2 and 3 and to the above described apron 11, the apron is put on or attached to the clothes of the workman by first tucking the flap portions 37, 39 interposedly between shirt 21 and pants 23, as best shown in FIG. 3. The upper portion 15 is then brought up and button hole 27 engaged on button 29.

60 In the above form of the invention the apron 11 is described as having yieldable tab fasteners 31, 33, and the following continuation of the specification describes an alternate suitable form of the invention designated in general as apron 41 which has similar characteristics to the above form, but has yieldable clip fasteners 43 instead of tab fasteners 31, 33 to attach the apron 41 to the clothes of the workman. In all other respects the aprons 11 and 41 are substantially the same.

65 Yieldable clip fasteners 43 are preferably formed of ductile metal wire of copper, aluminum or the like, and should be of such material and wire size as to be strong enough to attachably hold the apron in a working position and yet attached yieldably enough to permit the

apron to be quickly freed from the workman should it become caught in the machine.

Each of clip fasteners 43 is formed by making approximately two rectangular turns in a piece of wire, which turns include the larger outer turn 45 and the smaller inner turn 47. As is shown in FIG. 6, the two turns 45, 47 are substantially parallel to each other and joined in spaced relationship by a relatively short connecting portion 49 thereby forming the space 51 between the planes of the turns 45, 47 and forming the downwardly facing open end 53 of the clip fastener which leads to the space 51. The clip fasteners 43 are substantially laterally spaced and affixed along the waist 19 of apron body 11 on the inward side thereof, as best shown in FIG. 4. The placement of fasteners 43 on a slight curve, as viewed in FIG. 4, is desirable to facilitate close and neat fitting of the apron to the workman. As is best seen in FIGS. 5 and 6, each of the clip fasteners 43 is affixed to apron body 11 with the open end 53 downward and the connecting portion 49 upward, and is preferably affixed by consecutive loops of thread 55 drawn tightly around outer turn 45 and through portions of apron body 11 to secure the outer turn 45 in abutment with the inward surface of body portion 13.

Putting on the apron 41 and attaching it to the clothes of the workman is done in a manner similar to that previously described in attaching apron 11. In attaching apron 41, the clip fasteners 43 are hooked over belt 57, as shown in FIG. 6, with the outer turn 45 engaging the outside of the belt and the inner turn 47 engaging the inner side of the belt. The upper portion 15 is then brought up and fastened by engaging button hole 27 over button 29.

From the foregoing it will be understood that in both embodiments shown, i.e. aprons 11 and 41, the fastening means is completely covered by body portion 13 when the apron is in place on the workman so that no part of the fastening means is exposed. This is an important feature of the present invention since it makes the apron completely safe, as opposed to other types of aprons having attachment strings and other attaching means that can be caught in machinery. Thus, only the smooth outside surface of body portion 13 is exposed, and there is little chance of the apron getting caught in machinery. However, even if by chance the aprons 11, 41 were to get caught in a machine, which is not likely, it will be understood that the fastening means, i.e. flap portions 37, 39 or clip fasteners 43, will easily become detached from the workman's clothes so that there is absolutely no danger of the workman being drawn into the machine. It will further be understood that the length and width of aprons 11, 41 can be varied to fit the various physiques of the workmen without departing from the spirit and scope of the present invention. Also, it will be understood that in some cases where the workman is not wearing a shirt but only a T-shirt or the like, a safety pin, not shown, may be attached to the front of the T-shirt and used in the same manner as button 29 by slipping the safety pin through the button hole 27 to secure the upper portion 15 in place.

Although the invention has been described in some detail by way of illustration and example for purposes of

clarify or understanding, it is to be understood that it is not to be so limited since changes and modifications may be made therein which are within the full intended scope of this invention as hereinafter claimed.

5 I claim:

1. A workman's apron adapted to be worn as a covering over front parts of the shirt and pants of a workman comprising an elongated body having upper and lower portions and inward and outward sides, said upper portion being of solid fabric except the provision of a button hole adapted to engage a button on the front of the workman's shirt, and a substantially rectangular tab transversely affixed to said body on said inward side intermediate said upper and lower portions, said tab being adapted to be interposedly tucked between the workman's shirt and pants, and said apron including said tab being made substantially entirely of a sheet-like easily flexible and unstiff material.

20 2. A workman's apron adapted to be worn as a covering over front parts of the shirt and pants of a workman comprising an elongated body of thin flexible and unsupported sheet-like material having upper and lower portions and inward and outward sides, and a substantially rectangular tab of thin easily flexible and unstiff sheet-like material transversely affixed to said body on said inward side intermediate said upper and lower portions, said tab being adapted to be interposedly tucked between the workman's shirt and pants, the apron when subjected to a forceful pulling action being adapted to readily become disengaged from the clothes of the workman.

25 3. A workman's apron adapted to be worn as a covering over front parts of the shirt and pants of the workman comprising an elongated body having upper and lower portions and inward and outward sides, tab means affixed directly to said body on said inward side intermediate said upper and lower portions for interposedly tucking between the workman's shirt and pants and for subsequent easy withdrawal therefrom by an accidental pull on said apron body by a machine and the like to prevent the workman from being drawn therein; said tab means extending across a major portion of the width of said body and said tab means comprising a thin, unstiff and easily flexible fabric material.
